United States Patent Office

Des. 232,849
Patented Sept. 17, 1974

232,849

PET CHAIR

Mary E. Wilson, 30 Emerald Bay,
Laguna Beach, Calif. 92651

Filed Sept. 20, 1972, Ser. No. 291,362

Term of patent 14 years

Int. Cl. D30—06

U.S. Cl. D30—41

Fig. 3

Fig. 4

FIG. 1 is a perspective view of a pet chair embodying my new design;

FIG. 2 is a top plan view of the pet chair;

FIG. 3 is a front elevational view of the pet chair; and

FIG. 4 is an end elevational view.

I claim:

The ornamental design for a pet chair, substantially as shown.
